UNITED STATES PATENT OFFICE.

WILLIAM R. PARK, OF TAUNTON, AND BELVIN T. WILLISTON, OF SOMERVILLE, MASSACHUSETTS, ASSIGNORS TO THE HANCOCK INSPIRATOR COMPANY, OF BOSTON, MASSACHUSETTS.

DESIGN FOR A CASING FOR DOUBLE OR COMPOSITE INJECTORS.

SPECIFICATION forming part of Design No. 32,502, dated April 10, 1900.

Application filed February 23, 1900. Serial No. 6,312. Term of patent 14 years.

To all whom it may concern:

Be it known that we, WILLIAM R. PARK, of Taunton, county of Bristol, and BELVIN T. WILLISTON, of Somerville, county of Middlesex, Massachusetts, have invented and produced a new and original Design for the Casings of Double or Composite Injectors, of which the following is a specification, reference being had to the accompanying drawings, which form a part hereof.

In the drawings, Figure 1 shows in perspective an injector-casing shaped according to our design, and Fig. 2 a rear elevation of the same.

15 A represents the main body of the casing, and B a double-barreled projection from one end of the body A. The body is in general form a block or parallelepiped, approximating to a cube in its proportions. The barrel 20 B is substantially of the same width as the body A, but of considerably less depth. The end of the barrel B discloses twin circular openings K. The edges and corners of the body A are rounded or chamfered, so as to 25 present a smoothly-molded appearance and to avoid too abrupt angles. On either side of the barrel B where it emerges from the body A is a protrusion C. Circular apertures C' appear in the top of the protrusions C. On

a low trunco conoidal elevation on the top of the body there is a short cylindrical projection D. From the bottom of the body A there depends an extension A', which has cylindrical openings in its lower side. This lower extension A' has its sides and ends drawn in from the full width of the body, and the openings are placed centrally along a longitudinal median line.

A semicylindrical mouth G depends from the inner lower face of the barrel B. On the two forward corners of the top of the body A are raised the cylindrical apertured projections L.

In the butt-end of the body are located apertures H and J, symmetrically disposed with reference to the central vertical plane of the body, (denoted by the line x x', Fig. 2.)

We claim and desire to secure by these Letters Patent—

The design for a casing for double or composite injectors, substantially as shown.

Signed by us at Boston, Massachusetts, this 21st day of February, 1900.

WILLIAM R. PARK.
BELVIN T. WILLISTON.
